UNITED STATES PATENT OFFICE.

WILLIAM H. BUELL, OF NEW HAVEN, CONNECTICUT, ASSIGNOR TO E. I. DU PONT DE NEMOURS AND COMPANY, OF WILMINGTON, DELAWARE, A CORPORATION OF DELAWARE.

PRIMING CHARGE.

1,308,393.

Specification of Letters Patent.

Patented July 1, 1919.

Application filed August 31, 1917. Serial No. 189,115.

To all whom it may concern:

Be it known that I, WILLIAM H. BUELL, of New Haven, in the county of New Haven, and in the State of Connecticut, have invented a certain new and useful Improvement in Priming Charges; and do hereby declare that the following is a full, clear, and exact description thereof.

My invention relates particularly to priming charges for igniting powders of various kinds, including smokeless and black powders, especially as used in connection with center-fire and rim-fire ammunition, as, for example, small arms ammunition.

15 The object of my invention is to provide a primer which is specially suited for use in igniting the types of powders employed in firearms, and more particularly small arms.

20 Another object of my invention is to provide a priming charge of such a nature that, as a result of the combustion, there is an alkaline residue left, which tends to neutralize the acid residues in the gases produced

25 by the explosives present, thus preventing their deleterious action upon the bores of firearms.

A further object is to provide a priming charge containing an alkali-metal or an 30 alkaline-earth metal salt of tri-nitro-resorcinol, which is sometimes known as "styphnic acid" or "T. N. R."

35 A further object is to provide a priming charge which, owing to the presence of the salt of tri-nitro-resorcinol, which contains a very large percentage of oxygen, has the effect of producing a greater degree of heat of combustion, so as to bring about a complete and progressive ignition of the powder 40 in the cartridge, and so as to complete the combustion within the length of the bore of the firearm, and thus obviate variations in ballistics, muzzle flashes, etc.

45 A further object is, by the use of such salts, to provide priming charges which explode progressively, rather than by detonation, as in the case of mercury fulminate.

50 A further object is to provide priming charges which, by reason of the use of such salts, obviate the possibility of the amalgamation of mercury with the brass of the cartridge shell and other adjacent parts, which takes place when priming charges containing fulminate of mercury are used.

My invention is capable of being carried out in many different ways, but, for the purpose of illustration, I shall describe only certain forms of my invention hereinafter.

In general, such salts of tri-nitro-resorcinol may be prepared by simple neutralization of the alkali-metal hydroxid or carbonate by tri-nitro-resorcinol in a hot aqueous solution of the former, with subsequent cooling and precipitation. Where it is desired to produce a barium salt of tri-nitro-resorcinol, this may be prepared by precipitation from either a hot or a cold strong aqueous solution containing a mineral acid salt of barium, as, for example, barium chloride, to which is added an alkali-metal salt 70 of tri-nitro-resorcinol, in the presence of a weak organic acid.

While priming charges may be made in many different ways in accordance with my invention, I will describe in detail herein-after certain examples of priming charges made in accordance with my invention.

A priming charge made in accordance with my invention may be comprised of an alkali-metal or an alkaline-earth metal salt 80 of tri-nitro-resorcinol, as, for example, the barium salt, which may be referred to generically as a tri-nitro-resorcinate of an alkali-forming metal, either alone or mixed with an oxidizing agent and a fuel, or, if 85 desired, it may be used when mixed with a metallic sulfo-cyanate, as, for example, lead sulfo-cyanate, an oxidizing agent and a fuel; or it may be used when mixed with a heavy metal salt of tri-nitro-resorcinol, as, for example, a lead salt, an oxidizing agent, a fuel and metallic sulfo-cyanate.

90 For example, I may use for this purpose a composition comprising:

	Parts by weight.
Potassium tri-nitro-resorcinate or barium tri-nitro-resorcinate	15
Potassium chlorate	50
Antimony sulfid	35

100 Another composition which I may use would be the following:

	Parts by weight.
Potassium tri-nitro-resorcinate or barium tri-nitro-resorcinate	12 105
Lead sulfo-cyanate	25
Potassium chlorate	50
Antimony sulfid	13

Another composition which I may use would be the following:—

	Parts by weight.
Potassium tri-nitro-resorcinate	10
Lead tri-nitro-resorcinate	25
Potassium chlorate	35
Antimony sulfid	10
Lead sulfo-cyanate	20

10 It will be understood, however, that the proportions of the ingredients may be changed to a considerable degree as desired and so as to take into account the variations in the strengths of the ingredients as obtained in the trade.

Furthermore, in the place of the lead sulfo-cyanate, other sulfo-cyanates may be used, as, for example, the sulfo-cyanate of copper.

20 Again, in place of the potassium chlorate, some other oxidizing agent may be used, as, for example, potassium perchlorate or potassium nitrate, or chlorate of barium, or perchlorate of barium, or peroxid of barium.

25 If desired, further ingredients may be added to any of the compositions, as, for example, powdered glass, a substance which tends to make the mixture more sensitive.

While priming charges of this character 30 are capable of being used in many different ways and may be used in containers of many different types, I have shown only certain types of primers containing such charges in the accompanying drawings, in which—

35 Figure 1 shows a primer made in accordance with my invention and adapted to be applied to center-fire ammunition.

Fig. 2 shows a rim-fire shell provided with a charge of this character.

40 Fig. 3 is a plan view of the primer shown in cross-section in Fig. 1.

In the drawings, referring particularly to Fig. 1, I have shown a primer cup 1, in which a charge 2 of the priming composition has been seated by moistening it with a solution of gum, as, for example gum arabic or tragacanth, and then introduced into the cup 1 by heavy pressure. Thereafter the charge may be covered with a layer 50 3 of paper or tinfoil or a thin film of collodion or gum, as, for example gum arabic or tragacanth. An anvil 4 may then be inserted in the cup.

55 As shown in Fig. 2, a rim-fire shell 5 may be provided with a priming charge 6 by giving the priming charge a coating of the gum solution above referred to in connection with Fig. 1 and then seating it in the annular rim of the shell by centrifugal force. The 60 priming charge may then be covered by a layer 7 of collodion or gum, as, for example, gum arabic or tragacanth.

Priming charges made in this manner have not only the characteristics above re-

flected to, but are homogeneous in character, 65 and produce a uniform flame without an excess of pressure, but having the proper velocity and the intensity of heat to ignite the main charge before imparting to it any appreciable motion before ignition. Furthermore, the effect is to produce the maximum pressure within the breech of the fire-arm and not to delay the ignition until the charge is near the muzzle of the barrel, where the barrel is least adapted to withstand high pressure. 75

While I have described my invention above in detail, I wish it to be understood that many changes may be made therein without departing from the spirit of my invention. 80

I claim:—

1. A priming charge consisting of a mixture one of the constituents of which is a tri-nitro-resorcinate of an alkali-forming 85 metal.

2. A priming charge containing a tri-nitro-resorcinate of barium.

3. A priming charge containing a tri-nitro-resorcinate of an alkali-forming metal 90 and an oxidizing agent.

4. A priming charge containing a tri-nitro-resorcinate of barium and an oxidizing agent.

5. A priming charge containing a tri-nitro-resorcinate of an alkali-forming metal 95 and potassium chlorate.

6. A priming charge containing a tri-nitro-resorcinate of barium and potassium chlorate. 100

7. A priming charge containing a tri-nitro-resorcinate of an alkali-forming metal, an oxidizing agent, and a fuel.

8. A priming charge containing a tri-nitro-resorcinate of barium, an oxidizing 105 agent, and a fuel.

9. A priming charge containing a tri-nitro-resorcinate of an alkali-forming metal, an oxidizing agent, and antimony sulfid.

10. A priming charge containing a tri-nitro-resorcinate of barium, an oxidizing 110 agent, and antimony sulfid.

11. A priming charge containing a tri-nitro-resorcinate of an alkali-forming metal, an oxidizing agent, a fuel and a metallic 115 sulfo-cyanate.

12. A priming charge containing a tri-nitro-resorcinate of barium, an oxidizing agent, a fuel and a metallic sulfo-cyanate.

13. A priming charge containing a tri-nitro-resorcinate of an alkali-forming metal, an oxidizing agent, a fuel, and lead sulfo-cyanate. 120

14. A priming charge containing a tri-nitro-resorcinate of barium, an oxidizing 125 agent, a fuel, and lead sulfo-cyanate.

15. A priming charge containing a tri-nitro-resorcinate of an alkali-forming metal,

an oxidizing agent, a fuel, a metallic sulfo-cyanate, and a heavy metal tri-nitro-resorcinate.

16. A priming charge containing a tri-nitro-resorcinate of barium, an oxidizing agent, a fuel, a metallic sulfo-cyanate, and a heavy metal tri-nitro-resorcinate.

17. A priming charge containing a tri-nitro-resorcinate of an alkali-forming metal, an oxidizing agent, a fuel, a metallic sulfo-cyanate, and lead tri-nitro-resorcinate.

18. A priming charge containing a tri-nitro-resorcinate of barium, an oxidizing agent, a fuel, a metallic sulfo-cyanate, and lead tri-nitro-resorcinate.

In testimony that I claim the foregoing I have hereunto set my hand. 15

WILLIAM H. BUELL.
